FIG. 1 is a front view of a badminton racquet including a central portion of the badminton racquet;
FIG. 2 is a front view of the central portion of the badminton racquet of FIG. 1;
FIG. 3 is a first side view of the central portion of the badminton racquet of FIG. 1;
FIG. 4 is a rear view of the central portion of the badminton racquet of FIG. 1;
FIG. 5 is a second side view of the central portion of the badminton racquet of FIG. 1;
FIG. 6 is a front perspective view of the central portion of the badminton racquet of FIG. 1;
FIG. 7 is a top view of the central portion of the badminton racquet of FIG. 1; and,
FIG. 8 is a rear perspective view of the central portion of the badminton racquet of FIG. 1.
The ornamental design that is claimed is shown in solid lines in the drawings. The broken (dashed) lines shown in FIGS. 1 through 8 are included for the purpose of illustrating environmental elements only and form no part of the claimed design.
